UNITED STATES PATENT OFFICE.

ALFRED A. JACKSON, OF ARVADA, COLORADO.

FLOOR PLANING AND SCRAPING MACHINE.

1,109,335.

Specification of Letters Patent.

Patented Sept. 1, 1914.

Application filed February 16, 1914. Serial No. 818,898.

To all whom it may concern:

Be it known that I, ALFRED A. JACKSON, a citizen of the United States, residing at the town of Arvada, county of Jefferson, and State of Colorado, have invented certain new and useful Improvements in Floor Planing and Scraping Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in floor planing and scraping machines, my object being to provide an efficient construction of this character.

In my improved machine I employ an adjustable planing device located approximately midway of the frame in a lengthwise direction. This planing device is adjustable by a back and forth movement, whereby it is thrown into and out of the floor planing relation. The body of the planing device is trunnioned on the opposite sides of the frame. The trunnions engage elongated openings. When the trunnions are in the rear extremities of these openings, the device is in the lowermost position, and is adapted to engage the floor for planing purposes, while when the trunnions are in the forward extremities of the slots, the knife of the planer is raised above the floor. To the rear extremity of the main framework of the structure is attached the scraping device of the machine. This device is pivotally connected with the frame near its lower end, while its upper portion is provided with screw pins which pass through elongated openings in the main frame. By virtue of this construction the scraping device may be tilted upon its pivots to assume the proper position for scraping purposes. When properly adjusted, it is held in such position by tightening the screw pins.

Having briefly outlined my improved construction, I will proceed to describe the same in detail, reference being made to the accompanying drawing, in which is illustrated an embodiment thereof.

In the drawing,—Figure 1 is a side elevation of my improved machine. Fig. 2 is a similar view of the planing device shown in detail, and detached from the arms with which it is connected when in use. Fig. 3 is a vertical longitudinal section, taken centrally through the machine adjusted for planing purposes. Fig. 4 is a top plan view of the same.

The same reference characters indicate the same parts in all the views.

Let the numeral 5 designate the main framework of the machine, which consists of two side members 6 connected in front by two bars 7 and 8 which are also passed through the tongue or pull bar 9 of the machine. Also journaled in these side members 70 is an axle 10, to whose extremities are made fast wheels 12 which support the machine in front. In the rear the frame bars are further spaced, and connected by the scraper device 13, which is pivotally connected at 75 the rear extremity of the frame members and at the lower extremity of said device, as shown at 14. The upper extremity of this device is provided with screw studs 15 which pass through curved, elongated openings 16 80 formed in the opposite frame members. To the outer protruding extremities of these screw studs are applied wing nuts 17. By loosening these nuts the scraper may be turned on its pivots 14 until the knife 18 of 85 the scraper assumes the proper relation either for floor scraping purposes or for throwing it into the inactive position, as may be desired. When adjusted as shown in Fig. 3,—that is to say, with the screw 90 studs 15 in the lower extremities of the slots 16, the device is given its greatest angle of inclination; while if it is desired to cause the knife to approach the vertical position, the nuts may be loosened and the studs moved 95 upwardly in the said slots.

The knife 18 of the planing device is secured in place by means of screw studs 19 which are fixed in the body or frame of the device and pass through elongated openings 100 formed in the blade, and also through openings formed in an outside member 20 in which the studs fit. To the outer extremities of these studs are applied nuts 21 which are preferably of the wing shape, to facilitate hand manipulation. By loosening these

nuts the blade may be raised or lowered, as may be desired, and secured in the adjusted position by tightening the nuts.

Located forward of the scraping device, and about midway longitudinally of the frame members 6, is the planing device 22, which includes a body member 23, a knife 24, perforated to receive a stud 25 fast in the movable block 26. The knife is further secured in place by an exterior member 27 held in place by a set screw 28 threaded thereinto near its upper extremity, the inner extremity of the screw engaging the blade. Below the screw and located outside of the member 27 and about midway thereof is a transversely arranged pin 29 which forms a sort of fulcrum for the plate 27 when the screw 28 is tightened by forcing it against the knife. The knife is adjusted in the plane of its location by means of a screw 30 which is journaled in the body of the plane, its threaded portion 31 engaging a threaded opening formed in the block 26. The screw is locked against longitudinal movement by means of a collar 32 which engages the body of the structure at the upper extremity of the cavity 33 in which the block 26 is located. Hence, as the screw cannot travel in the block 26, the latter travels on the screw and carries the knife with it, whereby the knife may be raised and lowered at will. The body of the plane is provided with an opening 34 through which the lower extremity of the knife passes for floor engaging purposes.

The body of the plane is provided on opposite sides with trunnions 35 which enter grooves 36 formed in reinforced parts 37 of the frame members 6. The portions of the members 6 in front and rear of the parts 37 are relatively thin. The parts 37 are made of considerable thickness, however, in order to give the necessary width to the grooves and also close these grooves on the outside, whereby the trunnions of the plane are sealed. These grooves are closed at their rear extremities. The rear portions of the grooves are also lowermost, and when the trunnions engage these rear portions the plane is in position for use (see Fig. 3). From the rear portions of these grooves the latter extend upwardly and forwardly. When the trunnions are in the forward extremities of the grooves, the plane is elevated above its operating position, and when so adjusted the knife is free from engagement with the floor or other surface upon which the plane stands. In order to facilitate the manipulation of the plane, whereby its trunnions are moved back and forth in the grooves 36, arms 38 are perforated at their rear extremities to receive the trunnions 35. These arms are connected forward of the trunnions by a

rod 39. The forward extremities of the arms are also connected and properly spaced by a rod 40. These arms 38 are composed of relatively low parts 41. From the forward extremities of these parts 41 the arms extend upwardly, as shown at 42, and from the upper extremities of the parts 42 the arms extend forwardly, as shown at 43. The lower edges of the parts 43 are provided with recesses 44 and 45 adapted to receive the axle 10 of the machine. In other words, the arms 38 are adjusted between the members 6 of the main frame by changing the arms to cause their recesses 44 or 45 to engage the axle. When the recesses 45 engage the axle, the forward portion of the arms is supported by the axle, and the trunnions of the plane are in the rear extremities of the grooves 36. This is accomplished by moving the arms 38 forwardly a distance equal to that between the recesses 44 and 45, and during this movement the trunnions 35 move upwardly in their grooves and rest in the forward part 46 of said grooves.

This machine is adapted to be operated by hand,—that is, the user of the machine, through the medium of the tongue 9, draws the machine over the floor to be planed and scraped. When it is desired to perform the planing operation, the machine is adjusted as shown in Fig. 3.

In order that a machine of this character may properly perform its function, it is necessary that it be weighted, and for this reason a weight 47 of suitable mass is mounted on the frame members 6 to slidably engage them. It is locked in place by means of a screw 48 which passes through the weight, its lower extremity being threaded and passing through a securing spring 49, the spring being locked in place by a nut 50. When it is desired to lock the weight in the adjusted position upon the frame, the spring, which is bow-shaped, is so arranged that its opposite extremities 51 engage the under surfaces of relatively narrow rails 52 of the frame members 6. These rails are formed by making relatively large openings in the sides of the said members, the rails 52 bounding the said openings on their upper sides. When the apparatus is used for planing purposes, the weight is adjusted to occupy a position directly above the body of the planing device (see Fig. 3). When, however, it is used for scraping purposes, the weight is moved farther rearwardly, as shown in Fig. 1, whereby its downward force is exerted on the rear extremity of the frame, and consequently upon the scraping device. When the device is in use either for planing or scraping purposes, the weight may be moved to the extreme forward position shown in Fig. 1, whereby it will act to elevate the rear extremity of the

frame, and consequently the scraper. When in this position the operator may move the device from place to place with comparative ease. In order to allow the weight to 5 assume the dotted line position in Fig. 1, it is centrally recessed, as shown at 53, to make room for the tongue. In order to move the weight to this position, the locking spring 49 is thrown to the dotted line 10 position in Fig. 3, after which the weight may be moved forwardly, as illustrated by dotted lines in Fig. 1.

The forward extremities of the grooves 36 are open at the upper edges of the lower 15 rails 53 of the frame members 6, to permit the passage of the trunnions of the plane when it is desired to remove the latter.

The forward extremity 54 of the plane extends below and beyond the transverse 20 member 39 connecting the arms 38, as heretofore explained. By virtue of this construction the forward part of the plane is prevented from moving upwardly, and the rear part from swinging downwardly far- 25 ther than is desirable. It will be understood that the rear portion of the plane,—that is, the part extending in the rear of the trunnions, is heavier than the part extending forward of the same, and if it were 30 not for the construction just described, there would be a tendency, when the plane is not in use, for its rear portion to swing downwardly and its forward portion upwardly to a corresponding extent, which is undesirable. When it is desired to elevate the 35 forward portion of the main frame to a considerable extent, the axle of the wheels 12 may be removed from its normal position, as illustrated in the drawing, and placed 40 in lower openings 55 formed in the frame.

Having thus described my invention, what I claim is:

1. In a floor planing and scraping machine, the combination of a frame, a plane 45 trunnioned therein and longitudinally adjustable to vary its elevation, and a scraper also adjustably mounted on the frame, substantially as described.

2. A machine of the class described, including a main frame, a planing device 50 having trunnions, the frame having longitudinal grooves which the trunnions enter, the rear extremities of the grooves being lowermost, whence they extend upwardly and forwardly.

3. A machine of the class described, including a main frame, a planer device having trunnions, the frame having longitudinal grooves which the trunnions enter, the 60 rear extremities of the grooves being lowermost, the grooves extending upwardly and forwardly therefrom, their forward extremities being open above to permit the passage of the trunnions.

4. The combination of a main frame com-

posed of two members suitably spaced and having longitudinal grooves respectively formed therein, the rear extremities of the said grooves being lowermost, whence they extend upwardly and forwardly, and a plane located between said members and having trunnions engaging the said grooves and movable therein. 70

5. The combination of a main frame having longitudinal grooves whose rear extremities are lowermost, a plane having trunnions engaging the said grooves and movable therein, and means connected with the trunnions and extending forwardly therefrom to facilitate manual manipulation. 75

6. The combination of a main frame having longitudinal grooves whose rear extremities are lowermost, whence they extend upwardly and forwardly, a plane having trunnions engaging the said grooves and movable therein, and arms connected with the trunnions and extending forwardly therefrom to facilitate manual longitudinal adjustment of the plane in the frame. 80

7. The combination of a main frame having longitudinal grooves whose rear extremities are lowermost, whence they extend upwardly and forwardly, a plane having trunnions engaging the said grooves and movable therein, arms connected with the trunnions and extending forwardly therefrom to facilitate manual longitudinal adjustment of the plane in the frame, the forward portions of the said arms having spaced recesses, and a device extending transversely of the frame which the recesses of the arms are adapted to engage, whereby the plane is retained in the desired position of longitudinal adjustment. 90

8. In a machine of the class described, the combination of a main frame composed of two spaced members, front wheels, an axle mounted in the frame members which the wheels engage, a plane having trunnions engaging longitudinal grooves formed in the frame members, and arms whose rear extremities are connected with the trunnions and extend forwardly therefrom, the forward portions of the arms having longitudinally spaced recesses adapted to engage the axle to secure the plane in the desired position of longitudinal adjustment. 100

9. In a machine of the class described, the combination of a main frame composed of two spaced members, front wheels, an axle mounted in the frame members which the wheels engage, a plane having trunnions engaging longitudinal grooves formed in the frame members, and arms whose rear extremities are connected with the trunnions and extend forwardly therefrom, the said arms forward of the trunnions being provided with a transverse rod, the plane having a part extending forwardly of the trun- 110

nions and located underneath the said transverse member, for the purpose set forth.

10. A machine of the class described, comprising a frame whose forward portion is mounted on wheels, a planing device carried by the frame in the rear of the wheels, a scraping device located in the rear of the planing device, and a weight of suitable

mass longitudinally adjustable on the frame, substantially as described. 10

In testimony whereof I affix my signature in presence of two witnesses.

ALFRED A. JACKSON.
